UNITED STATES PATENT OFFICE.

MICHAEL OFFLEY, OF BALTIMORE, MARYLAND, ASSIGNOR TO HIMSELF AND WM. COLTON,
OF SAME PLACE.

SELF-LOCKING DEVICE FOR OMNIBUS-REGISTERS.

Specification of Letters Patent No. 29,549, dated August 7, 1860.

To all whom it may concern:

Be it known that I, MICHAEL OFFLEY, of the city of Baltimore, in the State of Maryland, have invented a new and useful Improvement in Omnibus-Registers, of which the following is a full, clear, and exact description, reference being had to the accompanying drawings, which make part of this specification, and in which—

10 Figure 1 represents a view in elevation of an omnibus register embracing my improvement, as seen from the front. Fig. 2 represents a similar view of the same, as seen from one side thereof, with the parts in the 15 same relative position as in Fig. 1, and Fig. 3 represents a diagram of the face-plate showing the relative position of the index-fingers at different times.

Omnibus-registers may be mainly divided 20 into two classes. The first class consists of those machines in which the registering mechanism is actuated by pulling upon a cord or lever, which is done sometimes by the driver of the vehicle, or by the person 25 who collects the fare, and sometimes by the passengers. The second class comprises those machines in which the registering mechanism is actuated by the weight of the passenger as he steps into or out of the omnibus. This latter class I deem preferable, 30 for in the former the registering is dependent upon the action of the driver, conductor, or passenger, and there can be no check against their carelessness or dishonesty, 35 while in the latter the movement is automatic, and, consequently, must take place whenever the weight of a passenger is thrown upon the moving mechanism, and can by no possibility register less than the 40 actual number of passengers carried.

The nature of my invention is such that it can readily be adapted to either of the abovenamed classes of registers, although I prefer the latter for the reason above stated, 45 and my improvement consists in the use of an independent index (in addition to those usually employed) rotating upon a shaft provided with an arm operated by a pin on one of the main wheels of the register, and 50 prevented from turning in but one direction, by which arrangement is caused to remain stationary during an entire revolution of the main wheel, and is then moved forward into a certain position where it remains fixed, 55 and from whence it cannot be moved either

backward or forward except by some one having access to the interior of the case inclosing the mechanism of the register, thus affording a valuable safeguard against fraud or carelessness on the part of the 60 driver, conductor or collector.

In the accompanying drawings a registering apparatus embracing my improvement is represented as applied to a city railroad car. The mechanism is to be inclosed in a 65 case (A) securely locked. The mechanism resembles that of ordinary clock-work and is contained between two plates (B, C) securely held together and kept a suitable distance apart by pillars (D). These plates 70 also form bearings for the shafts which carry the pinions of the register. The car is provided with a yielding step or platform (E) upon which each passenger steps as he enters the car. This step rests upon a lever 75 (F) one end of which is pivoted to the car while the other is attached to a connecting-rod or chain (G) which operates the lever that actuates the registering mechanism. A spring (f) under the step-lever (F) prevents 80 it from yielding too far when the weight is thrown upon it, and throws it up again as soon as the passenger steps off the platform.

The pawl-lever (H) to which the connecting-rod (G) is attached is pivoted at its inner end to a bracket or arm (I) secured upon, and projecting from the back-plate (C), and provided with suitable stops to limit the range of motion of the lever. 85 A spiral spring (h) may be employed to elevate the lever after each depression; or, it may be done by means of a spring (h') underneath the lever. Near the middle of the lever a pawl (h²) is pivoted. This 90 pawl takes into the teeth of a ratchet-wheel (J) turning upon a shaft (j); the pawl being held up to said teeth by means of a spring (h³) upon the lever H. There is also a spring and pawl (j') attached to the 100 back plate (C) to prevent the ratchet-wheel (J) from turning the wrong way when the lever H, is rising.

The shaft j, extends through the dial or face-plate (k) and carries an index or 105 pointer (J') upon its outer end. This shaft also carries a spur-pinion (j²) which gears into an intermediate spur-wheel (L) turning upon a shaft (l') which carries a pinion (l) gearing into a spur wheel (M). This 110

spur-wheel turns on a shaft (*m*) which extends through the dial-plate and carries an index (*M'*).

A small ratchet-pinion (*N*) is secured 5 upon a shaft (*n*) which, likewise, projects through the dial-plate, and carries upon its end an index (*N'*). This ratchet-pinion is also prevented from turning backward by means of a pawl (*n²*) held in place by a 10 spring. A short arm or projection (*n³*) is secured upon the face of the ratchet-wheel (*N*) and projects beyond its periphery in the same vertical plane. A pin (*m'*) which projects from the face of the wheel *M*, near 15 its periphery strikes against this arm (*n³*) when the parts are in their proper relative position, and carries it forward a certain distance, it then slips past the arm and the ratchet-wheel remains stationary.

20 The operation of the machine is as follows: Suppose the parts to occupy the position shown in Figs. 1, and 2, of the drawing, and that the fare for each passenger is five cents. Now, as a passenger steps 25 upon the platform (*E*) to enter the car, it sinks under his weight bearing down the step-lever (*F*) which, through the connecting-rod, (*G*) draws down the lever *H*, and pawl (*h²*). This causes the ratchet-wheel 30 *J*, to revolve the length of one tooth and the index *J'*, to point to half the distance between the points marked 100, and 5, in the drawings. As soon as the step (*E*) is relieved of the weight of the passenger the 35 parts are thrown up to their former positions by their respective springs; but the pawl *j'*, prevents any backward movement of the ratchet-wheel *J*. When the next passenger enters or some former one leaves the 40 car the same operation is repeated and the index *J'* marks the point 5. Thus it will be seen that two movements of the mechanism are necessary to register one fare, and that the registry is not completed until the 45 passenger has left the car. This process is repeated until twenty fares are registered, when the index *J'*, will register 100, on the dial *k*. The train of gearing is so proportioned that for every revolution of the index *J'*, the index *M'*, will register one point 50 (or one dollar) upon the dial *k'*. When twenty three dollars have been registered the pointers will occupy the position shown by the red lines in Fig. 3. As the movement

continues the pin (*m'*) on the wheel *M*, 55 strikes the arm (*n³*) on the small ratchet-pinion (*N*) and rotates it until its index (*N'*) marks the point 25, within the circle as shown in black lines in Fig. 3. As the pin (*m'*) continues its motion it slips past 60 the end of the arm (*n³*) and the ratchet-pinion (*N*) being held fast by the pawl (*n²*) the index *N'*, remains at the point 25 no matter how often the register may be operated after the pin *m'*, has once passed the 65 arm (*n³*). It will readily be perceived that this means of disconnecting the index after registering the required number of fares affords a great safeguard against fraud or 70 carelessness on the part of the driver or conductor. The register is to be set every morning by the starter who alone has access to it. The pawl *n²*, is provided with a handle to assist this adjustment.

I have described my improvement as applied to a city railroad car, but it is obviously equally applicable to any place where persons have to pass through a narrow space or doorway, as, for instance, in an omnibus, ferry-boat, bridge, or exhibition-room. It is also obvious that my improvement can be applied to use at any rate of fare, and the changes required to adapt the register to such fare are so obvious to any skilful mechanic as to require no detailed description in this place. It is likewise manifest that the capability of my improvement is not limited to amounts of aggregate fare.

I am aware that operating clock-work to 90 register passenger-fares either by the weight of the passengers themselves, or by pulling a cord or lever is not new; and therefore do not claim broadly any such device, but

Having thus fully described the construction and operation of my improved omnibus register, what I claim therein as new, and desire to secure by Letters Patent, is—

The combination of the pin *m'*, with the arm *n³*, when arranged for joint operation, 100 substantially as herein described for the purpose set forth.

In testimony whereof I have hereunto subscribed my name.

MICHAEL OFFLEY.
